UNITED STATES PATENT OFFICE.

HERMAN DOHL, OF ALTOONA, PENNSYLVANIA.

APPARATUS FOR MAKING CONCRETE WALLS.

SPECIFICATION forming part of Letters Patent No. 763,376, dated June 28, 1904.

Application filed September 30, 1903. Serial No. 175,215. (No model.)

To all whom it may concern:

Be it known that I, HERMAN DOHL, a citizen of the United States, residing at Altoona, in the county of Blair and State of Pennsylvania, have invented a new and useful Improvement in Apparatus for Making Concrete Walls, fully described and represented in the following specification and the accompanying drawings, forming a part of the same.

10 The object of the present invention is to provide a cheap, effective, and improved apparatus for making concrete walls.

This invention is particularly well adapted for building dams and other like heavy work, 15 as will hereinafter be more fully shown and described, reference being had to the accompanying drawings, wherein—

Figure 1 represents a plan view of a wall under construction employing the use of my 20 apparatus. Fig. 2 is a side elevation of the wall, showing the upright posts, mold-boards, and supporting-irons. Fig. 3 is a sectional view of the wall, showing the manner of placing the supporting-irons and their relation to 25 the molding-boards and upright posts, together with the binding-piece at the top, when applied to a straight wall. Fig. 4 is a view of my supporting-iron, showing how the one end is bent to retain the upright post and the 30 other to form an anchor when placed in the wall. Fig. 5 is a sectional view of a wall with succeeding steps as the wall becomes higher, showing the relative location of the parts with reference to the supporting-irons.

35 In making concrete walls I use my supporting-irons and proceed as follows, using similar letters to refer to similar parts wherever they occur on the different parts of the drawings.

40 The foundation of the wall being laid, I proceed by placing one of my supporting-irons A near the surface of the ground, sufficiently spaced to receive the vertical posts B B and the molding-boards C C. The supporting-bracket is then covered with concrete and left 45 until the wall is sufficiently strong to retain the iron and the load it is designed to carry. This being accomplished, I place the upright

posts B B in position and bind them at the top with the binding-piece D, which is notched 5c on the under side at d to receive the top of the upright posts B B. The molding-boards C C, I place as the height of the wall requires to hold the concrete in position until it is set. These molding-boards can be secured to the 55 posts B B in some suitable manner and handled in sections, using any number of boards desired in a section. The running-boards E E, I place in position last, which can be held in place temporarily by nailing to the binding-pieces D. This being accomplished, I begin filling the space between the molding-boards C C with concrete. Before the space between the supporting-irons A A and the binding-piece D is filled with concrete I place 60 another set of supporting-irons at G G and fill in around and above the brackets placed last to the top of the molding-boards C C. The brackets that I place last serve as a support for the centering pieces for the next 65 section of the wall, thus enabling me to build any height of wall without the use of bracing from the ground.

Fig. 5 shows the parts assembled in operative position when building walls with successive offsets as the height increases.

The wall having reached the height at which the offset is to be placed, the supporting-bracket A is put in position. A part of the body of the bracket is so placed as to be under the immediate surface of that part of the wall forming the step and located with reference to the rise of the wall so that the distance from the outer vertical part of the bracket to the wall is equal to the width of the 80 post B plus the thickness of the boards C C.

The bracket or supporting-iron I make of a suitable length, width, and thickness and forge the outer and inner ends (with reference to their place in the wall) such that they 90 will stand at right angles to the body of the bracket, thus making one end a retaining-leg for the upright post B and at the other an anchor that when set in the concrete will not be easily removed.

95 In this manner of building concrete walls I

am enabled to obviate the expense of bracing from the ground, which increases with the height of the wall.

What I wish to secure by Letters Patent 5 and claim is—

1. A wall-mold comprising supporting-irons having their inner ends embedded in the wall, vertical posts resting upon the outer end portions of the irons, horizontal mold-boards arranged at the inner sides of the posts and likewise supported upon the outer portions of the irons, and binding-pieces connecting the posts at the top.

2. A wall-mold comprising angled supporting-irons having their flanged inner ends em- 15

bedded in the wall, vertical centers or posts held at their lower ends upon the outer portions of the supporting-irons, mold-boards supported at the inner sides of the vertical posts, and binding-pieces connecting the vertical posts at the top and interlocked therewith, substantially as and for the purpose set forth. 20

In testimony whereof I have hereunto set my hand in the presence of two subscribing 25 witnesses.

HERMAN DOHL.
